UNITED STATES PATENT OFFICE.

JAMES B. GARNER, OF PITTSBURGH, PENNSYLVANIA, ASSIGNOR TO HOPE NATURAL GAS COMPANY, OF PITTSBURGH, PENNSYLVANIA, A CORPORATION OF WEST VIRGINIA.

PROCESS OF OBTAINING GASOLENE FROM HYDROCARBON GASES.

1,299,455.

Specification of Letters Patent.

Patented Apr. 8, 1919.

Application filed January 18, 1917, Serial No. 143,105. Renewed August 26, 1918. Serial No. 251,542.

To all whom it may concern:

Be it known that I, JAMES B. GARNER, residing at Pittsburgh, in the county of Allegheny and State of Pennsylvania, a citizen 5 of the United States, have invented or discovered certain new and useful Improvements in Processes of Obtaining Gasolene from Hydrocarbon Gases, of which improvements the following is a specification.

10 My invention relates to the recovery, from gases with which they are intermingled, of hydrocarbons whose boiling points at atmospheric pressure range from about 34° to 160° C., and which may be, and hereinafter 15 are, designated as gasolene regardless of whether the hydrocarbons are open chain and of the paraffin or olefin series or whether they are cyclic.

In United States Letters Patent No. 20 989,927, granted to G. M. Saybolt, there is disclosed a process for obtaining naphtha or gasolene from combustible gas of natural origin and underground source, such method, briefly stated in the general terms of the 25 patent, consisting in subjecting the gas under pressure to a naphtha absorbing menstruum for the purpose of separating from the gas such naphtha as is liquid at atmospheric temperature and pressures, and in 30 subsequently removing the naphtha from the menstruum.

While my invention contemplates the use 35 of an absorption process similar to that disclosed in the Saybolt patent, it is, as indicated above, unlimited to the recovery of gasolene from natural gas, but extends to its recovery from any gas or gases with 40 which it may be intermingled. As an example of gases, other than natural, from which gasolene may be recovered, it has been 45 found that large quantities of gas are formed in the practice of the various processes for cracking petroleum to produce gasolene, and that such gases include gasolene hydrocarbons, that is, hydrocarbons whose 50 boiling points lie within the above stated range.

In practising absorption processes, for the 55 recovery of gasolene from hydrocarbon gases with which it is associated, one of the greatest sources of difficulty is the presence in the menstruum of the lighter constituents of the gas. Under the pressures which, to obtain substantial yields of gasolene, it

is necessary to place the gas when subjecting it to the absorbing menstruum, it has been found impossible to prevent some of the lighter constituents of the gas from being absorbed by the menstruum. When, for the purpose of distilling the menstruum, the high absorption pressure is diminished or removed (as it must be to practise the process in a practical and economic manner), the absorbed lighter constituents of the gas volatilize, choke up the apparatus, and prevent to a large extent the distillation of the gasolene from the menstruum and also prejudicially effect the subsequent condensation of the gasolene vapors.

It is therefore the object of my invention 70 to provide a process for the purpose and of the general character described, whereby the lighter constituents of the gas absorbed by the menstruum may be effectively removed 75 from the menstruum prior to the distillation thereof.

In the practice of my invention the gas to be treated is subjected to the absorbing menstruum under such high pressures as are required to effect the removal from the gas of 80 large portions of its gasolene content. As already stated some of the lighter constituents of the gas will be absorbed by the menstruum when the absorption step is performed under high gas pressure. To remove 85 these lighter constituents I expose the menstruum, after it has been used for high pressure absorption, to the gas at low pressure and before the gas has been subjected to high pressure absorption. By thus exposing the menstruum to the gas at low pressure, the lighter and more volatile gaseous constituents are vaporized and are again carried with the main body of gas through 90 the menstruum in the high pressure absorbers. With respect to this, it has been found that the quantity of lighter constituents absorbed by the menstruum varies little if any 95 with relation to the proportion of lighter constituents in the gas, so that the addition 100 to the gas of the lighter constituents previously absorbed by the menstruum will not have the effect of subsequently increasing the amount of lighter constituents absorbed. After the menstruum has been thus exposed 105 to the low pressure incoming gas it is distilled for the removal of its absorbed gasolene constituents.

Manifestly this process is well adapted to the treatment of gases of low pressure origin, such as casing-head and flow-tank natural gases, these gases being usually obtained at, or at less than, atmospheric pressure. To recover substantial yields of gasolene from them, they must be compressed. By effecting such compression at the absorption plant, the menstruum with its absorbed gasolene and lighter constituents may be exposed to the incoming gas prior to its passage through the compressor, and this may be done without additional operating expense.

The menstruum may, for the removal of its lighter absorbed constituents, be exposed to the low pressure gas in any desired manner. However, this is preferably done by passing the low pressure gas through the menstruum when the menstruum is in the form of a spray. By such procedure the menstruum will, in addition to giving up its lighter constituents, further absorb some of the heavier gasolene-forming constituents of the gas.

In the accompanying drawing there is diagrammatically shown an apparatus for practising the invention in the preferred manner just stated.

Referring to the drawing, the low pressure gas, from whatever source of supply it may be taken, flows through a pipe 1 to a tank 2 in which there are a plurality of nozzles 3 connected to a header 4, which header is in turn connected to a conduit leading from the body of menstruum through which the gas under high pressure has been passed to effect the absorption of gasolene-forming hydro-carbons. The pressure being thus removed from the menstruum while the menstruum is exposed to the low pressure gas, the lighter gaseous constituents previously absorbed by the menstruum become volatilized and intermingled with the gas. From the tank 2 the gas and menstruum flow through a conduit 5 to a tank 6. To the end that the finely divided particles of menstruum carried by the gas from the tank 2 may not enter the compressor, the conduit 5 extends to a point near the bottom of the tank 6 and the level of the menstruum within such tank is maintained above the outlet of the conduit, as indicated. From the tank 6 the gas is taken by a pipe 7 to a compressor 8, and is thereafter cooled by a cooler 9. Manifestly the compressor may, if desired, be used to create a partial vacuum in the pipe 1 for the purpose of drawing of the gas from, for example, a flow-tank, casing-head or still.

The compressed gas may be subjected to the absorbing menstruum in any desired manner. Preferably it is passed first through a spray absorber and then through a liquid-body absorber. The spray absorber,

as shown herein, may comprise a tank 10 turned downwardly at one end to form a trap for the menstruum, and a plurality of spray nozzles 11 connected to a header 12. The gas, after flowing through sprays in the tank 10, flows through a pipe 13 to a perforate header 14 in the bottom of a liquid-body absorbing tank 15, and from this header the gas percolates through the liquid body of menstruum, the unabsorbed constituents being caught in a header 16 and carried through a line 17 to any desired point of consumption. The purpose of the liquid-body absorber is twofold, first to remove from the gas the finely divided particles of menstruum carried by the gas from the spray absorber, and secondly, to effect further absorption by the menstruum of the gasolene constituents of the gas.

Considering the entire apparatus as a whole, the gas and menstruum flow in counter currents through it. The menstruum, substantially free from absorbed gas constituents, enters one end of the tank 15 through a pipe 18, flows slowly through such tank, and is taken from it through a pipe 19. The pressure of the gas in the tanks 10 and 15 being substantially the same, a pump 20 is placed in the line 19 to cause the menstruum to properly flow through such line to the header, and from thence through the spray nozzles 11 within the tank 10. The menstruum collected in the trap portion of the tank 10 is conducted through pipes 21 and 36 to the header 4, the valves 22 and 23 of these pipes being open. The latter of these valves is placed adjacent to the header to prevent, as far as possible, the foaming of the menstruum in the pipes 21 and 36 when the pressure is relieved from the menstruum, such foaming being due to the volatilization of the lighter gas constituents previously absorbed by the menstruum in the high pressure absorbers.

The exposing of the menstruum in the tank 2 to the low pressure gas, and the consequent removal of the absorbed lighter gas constituents, have already been explained. The next step in the process is the removal from the menstruum of its absorbed gasolene. For this purpose the menstruum is conducted through a pipe 24 to a still 25, in which it is heated to the required temperature to vaporize the absorbed gasolene. The vapors generated in the still are carried therefrom through a pipe 26 to a condenser (not shown) which may be of any well known or desired construction. As indicated, the pipe 18 for conducting the distilled menstruum from the still to the absorbing tank 15, and the pipe 24 for conducting the menstruum to the still pass through a suitable heat exchanger 27 which also may be of any preferred construction. The menstruum flowing to the tank 15 may be

further cooled by a cooler 28, and both the pipes 18 and 24 may be provided, respectively, with pumps 38 and 29.

In case it is desired to use only the liquid-body absorber, the gas, after being compressed, may be conducted through a pipe 30 from the pipe 7 to the pipe 13, and the menstruum may be conducted through a pipe 31 from the pipe 19 to the pipe 36, thus bypassing the spray absorber. For this purpose it is only necessary to close the valves 22, 32 and 33 of pipes 21, 7 and 19, respectively, and to open the valves 34 and 35 of pipes 30 and 31.

While my invention is, in its broader aspects, unlimited to the relative or absolute pressures of the gas in the gasoline-absorbing and menstruum-exposing step of the process, the best results are obtained when the incoming low-pressure gas is at substantially atmospheric pressure, and when, for gasoline-absorption, the gas is compressed to thirty or more pounds per square inch.

With respect to the absorbing menstruum, various liquids having an affinity for the gasoline-forming hydrocarbons may be used. However, the preferred liquid is petroleum hydrocarbons having an initial specific gravity of from 28° to 55° Baumé at 60° F.

It is apparent that other forms of apparatus than those specifically shown and described may be used in the practice of my invention.

I claim as my invention:

1. The process of obtaining gasoline from hydrocarbon gases containing it, which consists in subjecting the gas under a pressure substantially greater than atmospheric pressure to a gasoline-absorbing menstruum; thereafter, for the removal from the menstruum of the lighter constituents absorbed thereby, exposing the menstruum to the gas at a pressure substantially lower than said first named pressure and prior to said higher pressure subjection of the gas to the menstruum; and thereafter removing the gasoline from the menstruum.

2. The process of obtaining gasoline from hydrocarbon gases containing it, which consists in subjecting the gas under a pressure 50 of not less than about thirty pounds to the square inch to a gasoline-absorbing menstruum; thereafter for the removal from the menstruum of the lighter constituents absorbed thereby, exposing the menstruum 55 to the gas at a pressure substantially lower than said first-named pressure and prior to said high pressure subjection of the gas to the menstruum; and thereafter subjecting the menstruum to a distilling operation for 60 the removal of its absorbed gasoline.

3. The process of obtaining gasoline from hydrocarbon gases containing it, which consists in subjecting the gas under a pressure substantially greater than atmospheric pressure 65 to a gasoline-absorbing menstruum; thereafter for the removal from the menstruum of the lighter constituents absorbed thereby, spraying the menstruum into the line of flow of the incoming gas at a pressure 70 substantially lower than said first named pressure; and thereafter subjecting the menstruum to a distilling operation for the removal of its absorbed gasoline.

4. The process of obtaining gasoline from 75 hydro-carbon gases containing it, which consists in subjecting the gas under a pressure not less than about thirty pounds to the square inch to a gasoline-absorbing menstruum; thereafter, for the removal from the 80 menstruum of the lighter constituents absorbed thereby, spraying the menstruum into the line of flow of the incoming gas at substantially atmospheric pressure; and thereafter subjecting the menstruum to a 85 distilling operation for the removal of its absorbed gasoline.

In testimony whereof I have hereunto set my hand.

JAMES B. GARNER.
